UNITED STATES PATENT OFFICE.

ALEXANDER JAY WURTS, OF PITTSBURG, PENNSYLVANIA, ASSIGNOR TO THE WESTINGHOUSE ELECTRIC AND MANUFACTURING COMPANY, OF SAME PLACE.

CIRCUIT-BREAKER.

SPECIFICATION forming part of Letters Patent No. 570,419, dated October 27, 1896.

Application filed May 29, 1896. Serial No. 593,623. (No model.)

To all whom it may concern:

Be it known that I, ALEXANDER JAY WURTS, a citizen of the United States, residing in Pittsburgh, in the county of Allegheny and State of Pennsylvania, have invented a new and useful Improvement in Circuit-Breakers, (Case No. 703,) of which the following is a specification.

My invention relates to circuit-breakers, and has particular reference to circuit-breakers which are employed in connection with high-potential circuits carrying currents of considerable volume, it being specially designed for use in stations supplying current to electric-railway circuits, although not limited to that specific use.

One of the objects of my invention is to provide a circuit-breaker which may be readily closed by the application of a comparatively slight force, so as to make a perfect contact between its engaging terminals, and which will open automatically and without frictional resistance whenever the current in the circuit increases materially beyond a predetermined maximum limit.

A further object of my invention is to provide an improved means whereby any material increase of current beyond the predetermined limit will serve to suddenly release the movable member of the breaker, whether the increase of current to or through the critical maximum amount be gradual or sudden.

A further object of my invention is to provide a breaker which may be opened under any amount of load without any injury to the main contact-terminals by reason of the formation of arcs between the same.

A further object of my invention is to provide a breaker in which the arc formed by the separation of the shunt-contacts shall be horizontal, and therefore easily interrupted, and which shall be above the main portion of the apparatus, where it will be least likely to have any injurious effect.

Referring to the drawings, Figure 1 is a view, partially in section and partially in side elevation, of my circuit-breaker in closed position. Fig. 2 is a similar view showing the circuit-breaker partially closed, certain parts being broken away. Fig. 3 is a detail perspective view of the movable shunt-contact-

supporting plate. Fig. 4 is a front elevation of the circuit-breaker in open position. Fig. 5 is a detail sectional view, the section being on line *x x* of Fig. 4; and Fig. 6 is a detail view, upon a smaller scale, of the stationary shunt contact-terminals, looking downward from the rear of the switchboard.

Reference being now had to the drawings in detail, 1 is the base or switchboard panel upon which the operative parts of the switch are mounted, and which may be constructed of marble or other suitable insulating material.

2 is a hollow block or casting, which is provided with the usual leaf-spring jaws 3, for the reception of the arm 4 of the movable member of the circuit-breaker when it is thrown open. The arm 4 is journaled at its inner end upon a pintle 5, mounted and free to turn in the casting 2. A stop-piece 6, having a lug 6^a, is mounted upon the pintle 5 and rigidly fastened to it by a set-screw 7. A block 8 is pivoted to the piece 6 and bears against the upper end of a coiled spring 9. A rod 10 depends from the block 8 and serves to retain the spring 9 in its proper position. The arm 4 is provided with the usual handle 11 and also with a small roller 12, the latter being in position to be engaged by the hook 13 at the end of latch 14 when the breaker is closed. The contact portion of the movable member of the breaker is a bar or plate 15, to which are fastened, preferably at its upper edge, two curved contact-springs 16, the purpose of which will be hereinafter more fully described.

Suitably fastened to the bar or plate 15, and preferably between the same and the adjacent portion of the arm 4, is a spring-plate 17, preferably formed of copper, and having two curved end portions projecting beyond the bar 15. Fastened to each projecting end of this spring-plate is an auxiliary contact-piece 18, comprising a block 19, formed of carbon or some other good conducting material, which is practically infusible, and a plate 20, of copper or other metal having a high degree of conductivity. I prefer to form the blocks 18 of carbon, but I do not desire to limit my invention to this material, for the reason that graphite or some other composition which

has the necessary conducting properties and is practically infusible by electric arcs may be employed in lieu thereof. Each metal plate 19 is set into a recess which is formed 5 in the outer face of the block 18 and extends through a portion only of its length, so that the outer face of the plate and that of the free end of the block combine to form a single smooth contact-surface. The contacts 17 10 being connected by a single copper plate, a good conducting-path between them is insured irrespective of the character of the contact between the said plate and the bar 14.

The ends of the supporting-spring 16 are 15 preferably clamped between the blocks 18 and plates 19, so as to make good electrical contact with the said parts.

I prefer to give the faces of the contact-pieces 17 the form of the arc of a circle struck 20 from the center of the pindle 5 when the circuit-breaker is closed. These contacts are also slotted longitudinally, as clearly indicated in Fig. 4, such slots extending a short 25 distance into the supporting spring-plate, in order that the contacts may adapt themselves to any irregularities in the surface of the stationary contact-terminals with which they engage.

Each of the main stationary contact-terminals 20 consists of a bundle of thin plates 30 which are clamped together and to a projection on a supporting base-piece 21. The inner end of each contact-terminal is also preferably united to the part 21 by solder or amalgam. These laminæ, or the larger portion of them, terminate in a plane which is inclined 35 at such an angle to the base of the circuit-breaker that the contact bar or plate 14 will make a close contact therewith. The angle 40 of the plane of the contact ends of these laminæ is also such that the bar or plate 14 will engage them one after another, beginning with the outermost one, in closing the breaker, thus successively lifting or deflecting 45 each of the said ends slightly from its normal position.

As will be seen by reference to Figs. 1 and 2 of the drawings, this operation results in a maximum deflection of the free ends of the 50 outer laminæ and in little or no deflection of the innermost ones. A sliding engagement between the parts 14 and 20 is also effected, which helps to insure a good contact between them and keeps the contact surfaces bright 55 and clean. While I prefer to form these contacts of thin copper plates, it will be understood that the individual elements of which the contact is composed may have any other form in cross-section which may be found 60 convenient, provided they are sufficiently resilient to effect the desired result.

Suitably fastened, preferably by means of bolts, to a projection on each supporting-piece 65 21 is a spring-plate 22, to the outer end of which is fastened a terminal contact 23, with which the corresponding movable contact 17 engages. Each of these contacts 23 comprises

a block 24 and a plate 25, which are preferably made of the same materials as are the corresponding blocks 18 and plates 19 of the 70 contacts hereinbefore described. The curvature of the contact-faces of the contacts 23 is also the same as that of the faces of contacts 17, except that it is concave instead of convex. This curvature of the engaging 75 faces of the shunt-contacts insures a good electrical contact between the entire engaging surfaces, not only when the breaker is closed, but during the opening of the same, until the metal portions of the contacts are 80 separated.

The construction of the shunt-contacts partially of metal and partially of carbon, or some other substantially infusible conducting material, is an important improvement 85 over the carbon shunt-contacts which have heretofore been employed in this class of devices.

In the employment of shunt-contacts made entirely of carbon in circuit-breakers employed to open circuits carrying heavy currents it has been found that the carbon was not a sufficiently good conductor to shunt all of the current around the main circuit-terminals, and that consequently such main circuit-terminals often became seriously injured by the arcs, due to the unshunted current, so much so, in fact, that it was necessary to cut away the blistered surfaces before the switch could be again closed. With the present construction of shunt-contacts it will be readily seen that a complete metal path is provided for the current until the main contacts have become separated a considerable distance, and that consequently the entire current will be 100 shunted. The conductivity of the shunt-path for the current is also materially improved in the form of circuit-breaker shown by curving the metal contact-faces in the manner above described. When the metal contact-plates of the shunt become separated, the current will obviously be compelled to take the path provided by the infusible material, so that the final interruption will occur, as in the old form of breaker, where the resulting 115 arcs can do little, if any, damage. These stationary shunt contact-blocks also have their free ends beveled or inclined toward each other, as indicated most clearly in Fig. 6, in order that the interruption of the current shall 120 occur at their outermost points. This feature of construction is desirable in order that the contacts may be placed near enough together to make a compact structure without danger of arcing across from one terminal to the other. 125

The location of the stationary shunt-contacts side by side above the main body of the breaker is desirable, since the arcs formed between the separated terminals are substantially horizontal, and therefore easily interrupted, and, furthermore, all danger of injury to the main terminals is substantially avoided by reason of such location. Any tendency to arcing between the stationary contacts is 130

largely counteracted by the repelling action excited by the arcs against each other.

Instead of employing a solenoid or magnet coil for actuating an armature to release the movable member of the circuit-breaker when the current increases beyond the predetermined limit, as is usual in this class of devices, I utilize one of the main contacts of the circuit-breaker for this purpose, and in lieu of the usual solenoid or magnet core I provide a body of magnetizable metal, preferably in the form of a band 26, which partially surrounds the stationary contact, and is of sufficient width and thickness to provide a good magnetic circuit. As shown in Fig. 4 of the drawings, this band 26 is fastened in position by means of the bolts which fasten the contact 20 to the base-piece 21, and is bent around the edges of the contact in such manner that the end near the central line of the breaker projects somewhat beyond the face of the contact and at right angles to the plane of its back, the other end projecting a materially less distance. This particular form of band is not essential, but it has been found operative and useful in practice.

Below the stationary contacts and substantially midway between them is located a block or casting 27, provided at one side with an arm 28, between which and the base of the casting is pivoted a bar-armature 29. This armature 29 is provided with an opening 30 midway between the stationary contacts, through which extends a bolt 31, the head of which rests upon the upper surface of the armature. The bolt 31 also extends through a similar opening in the latch 13, and is provided with a nut, so that when the armature is actuated by the magnet above described the first part of its movement will serve to raise the bolt until the nut is brought into engagement with the latch 13, and a further movement will serve to withdraw the latch from the roller 12, thus permitting the movable member of the breaker to be instantly thrown back by the action of the spring 9. The lost motion between the armature and latch is employed in order to permit the armature to enter the strongest part of the magnetic field before acting upon the latch, thereby insuring an effective and sudden releasing blow.

In order to insure the retention of the movable member of the breaker in its closed position until the volume of current at which it is designed to open is reached, and to insure a sudden tilting of the armature and consequent withdrawal of the latch when the current reaches the maximum allowable limit, I provide the second stationary member 20 of the breaker with an iron band 26^a, preferably of the same shape as the band 26, except that the portions adjacent to the edges of the contact are materially shorter than the corresponding portions of the band 26, in order that the number of lines of force passing through the adjacent end of the armature shall be less than the number threading the opposite end.

The necessity of some expedient whereby the pull of this magnet shall be made weaker than that of the other is obvious, since the magnetic pull at this end constitutes a load which must be overcome in order to effect the withdrawal of the latch; but it will be understood that means different from that shown, whereby the strength of the magnet or the action of the same upon the armature is modified, may be employed, if desired. The character of the load is such that when the pull upon the opposite end of the armature is sufficient to overcome it the tripping action will occur with a sharp, sudden jerk, which is particularly effective and desirable in this class of apparatus. I also provide the load end of the armature with a small set-screw 32, the inner end of which bears against the outer end of the band 26^a, and is adjustable in order to provide for different loads. I prefer to make this screw of magnetizable metal in order that it may serve as a saturated element in the magnetic circuit; but it may be made of other material, if desired. Any other suitable adjustable device may also be employed in lieu of the screw.

33 is a bar or rod provided with a suitable scale and supported from the armature and parallel to it by means of rods 34. A weight 35 is mounted upon the bar 33 in such manner that it may be moved back and forth thereon in accordance with the critical load for which the breaker is to be set.

36 is a screw for clamping the weight 35 at any desired position on the bar 33.

37 and 38 are bars or strips provided with outwardly-projecting upper ends and with handles at their lower ends. These bars have a slot-and-pin connection with the base 1 and serve, respectively, when pressed upwardly to tilt the armature in the one direction or the other.

It will be understood from the foregoing description that the breaker may be set by means of the screw 32 and weight 35 to open upon any desired load, and that when such load is reached the latch will be withdrawn with a sudden jerk due to the sudden release of the armature by the load-magnet and the lost motion between the latch and armature. The spring 9 will then act through the parts 8, 6, and 6^a to separate the contacts, after which the arm 4 will fall away from the lug 6^a and between the leaf-springs 3, by reason of the impetus imparted by the spring 9 and the action of gravity.

Immediately upon the separation of the main contacts, which will occur without material frictional resistance, the entire current will be shunted through the copper plates 19 and 25 and the spring-supports 16 and 22. When the plates 19 and 25 become completely separated, the current will be forced to take the path through the infusible blocks 18 and 24 and will be finally interrupted at the outermost corners or tips of these blocks. It is therefore apparent that under ordinary cir-

5 cumstances all possibility of injury to the main contacts of the breaker is obviated. Should it happen, however, that the current should not be entirely shunted through the 15 auxiliary contacts, any current which fails to take that path will be interrupted between the springs 15 and the outer sides of the ends of the stationary contacts, where it will do little, if any, harm.

10 I claim as my invention—

15 1. In a circuit-breaker or switch, the combination with main contact-terminals of a shunt around the same provided with separable contacts each of which has a metal portion and an infusible conducting portion so arranged that the current will be first shunted through the metal and then through the infusible portions.

20 2. In a circuit-breaker, the combination with a pair of stationary main circuit metal contacts and a bridging movable contact, of a pair of auxiliary stationary contacts and a pair of electrically-connected contacts coöperating therewith to form a shunt around the 25 main contacts, said auxiliary contacts having metal portions which are in engagement when the switch is closed and which do not move out of engagement until the main terminals have become separated, also having infusible 30 conducting portions, which engage with each other after the metal portions become separated, and the separation of which interrupts the current.

35 3. In a circuit-breaker or switch, the combination with stationary and movable main-circuit contact-terminals, of a pair of spring-supported contact devices electrically connected with the stationary main circuit-terminals and a movable pair of spring-supported 40 contact devices electrically connected together and supported by the movable main circuit-terminal, both sets of spring-supported contacts having metal engaging portions and carbon engaging portions, the separation of 45 said carbon portions serving to interrupt the current.

45 4. In a switch or circuit-breaker, the combination with a pair of stationary main-circuit contact-terminals, of a movable main-circuit contact-terminal bridging said stationary 50 contact-terminals and provided with detachable pieces for making final contact therewith, and a shunt around said main-circuit contact-terminals provided with separable contacts the engaging portions of which are partially of metal and partially of infusible 55 conducting material.

55 5. In a switch or circuit-breaker, the combination with a pair of stationary main-circuit contact-terminals, of a movable main-circuit contact-terminal bridging said stationary contact-terminals and provided with detachable contact springs for making final contact therewith, and a shunt around said main circuit-terminals provided with separable contacts the engaging portions of which are partially of metal and partially of carbon.

6. In an automatically-opening switch or circuit-breaker, the combination with separable main circuit-contacts, of combined metal and carbon contacts provided with spring-supports and located in a shunt around the main circuit-contacts, means for releasing the movable contacts and means for separating the same from the stationary contacts. 70

7. A circuit-breaker having a pair of main stationary contacts and a single bridging movable contact, in combination with a pair of stationary shunt-contacts and a pair of coöperating movable contacts connected by a single spring-plate conductor. 75

8. In an automatic circuit-breaker, the combination with a pair of stationary contacts, an iron band partially surrounding each of them, a bridging movable contact and a latch therefor, of a pivoted armature having an adjustable projection at one end normally bearing against the adjacent iron band, and a longitudinally-adjustable weight on the other end. 85

9. In an automatic circuit-breaker the combination with the separable contacts and a locking device therefor, of a releasing-armature, and a body of magnetizable metal adjacent to said armature and partially surrounding one of the circuit-terminals. 90

95 10. In an automatic circuit-breaker the combination with the separable contacts, a latch and means for separating the contacts when the latch is withdrawn, of a pivoted armature having a lost-motion connection with said latch and a body of magnetizable metal partially surrounding one of the circuit-terminals and having an air-gap adjacent to said armature. 100

105 11. In an automatic circuit-breaker, the combination with a pair of stationary contacts and iron bands partially surrounding the same, of a movable bridging contact, means for locking the same in closed position, a pivoted releasing-armature and an adjusting means interposed between one end of the same and the adjacent iron band. 110

115 12. In an automatic circuit-breaker, the combination with a pair of stationary contacts, a movable contact bridging the same, a latch, and means for separating said contacts upon the withdrawal of the latch, of a latch-withdrawing armature, bodies of magnetizable metal partially surrounding the respective stationary contacts and acting upon the armature in opposition to each other, said parts being so constructed and arranged that the pull exerted by one magnet may be overcome by that of the other, when the current in the circuit exceeds a predetermined limit. 120

125 13. A circuit-breaker having separable main contacts and auxiliary shunt-contacts located side by side above the main contacts, the outer ends of the stationary members of said shunt-contacts being beveled or inclined inward toward each other, whereby the circuit will be finally interrupted at the outer corners of said contacts. 130

14. In a circuit-breaker, the combination

with the main stationary and movable contacts, of a pair of stationary shunt-contacts, and coöperating contacts carried by and movable with the corresponding main contact 5 member, the engaging faces of said shunt-contacts having a curvature of substantially the arc of a circle struck from the pivotal support of the movable member as a center.

15. In a switch or circuit-breaker, a solid movable contact-terminal in combination with a coöperating stationary terminal consisting of a bundle of conductors the contact ends of which are in a plane which is inclined with reference to the position of the individual 15 conductors and which are engaged by the contact-face of the movable terminal in succession beginning with the outermost ones in closing the breaker, whereby said ends are successively deflected slightly from their normal 20 positions and a lateral pressure is exerted against them.

16. In an automatic circuit-breaker, the combination with a pair of stationary contacts each consisting of a bundle of conductors 25 ors the contact ends of which lie in a plane inclined with reference to the position of the individual conductors, of a solid bridging contact bar or plate movable into and out of con-

taet with said contact ends, the engagement being made successively with said ends, beginning with the outermost ones, whereby they are successively deflected from their normal positions, means for locking said movable contact in its closed position and means actuated by an excessive current in the circuit to unlock said movable contact.

17. In an automatic circuit-breaker, the combination with a movable contact bar or plate, and a pair of laminated stationary contacts, substantially perpendicular to the supporting-base and having inclined contact-faces along which the movable contact-bar has a limited sliding movement, whereby the ends of the laminæ are successively deflected from their normal positions, of means for locking 45 said contacts in engagement and means actuated by an excessive current for unlocking the same.

In testimony whereof I have hereunto subscribed my name this 26th day of May, A. D. 50 1896.

ALEXANDER JAY WURTS.
